UNITED STATES PATENT OFFICE.

THURE LARSSON, OF WORCESTER, MASSACHUSETTS, ASSIGNOR OF ONE-THIRD TO WILLIAM E. D. STOKES AND ONE-THIRD TO FREDERICK A. JONES, BOTH OF NEW YORK, N. Y.

AUTOMATIC STOPPING MECHANISM FOR ELEVATORS.

1,127,032.

Specification of Letters Patent.

Patented Feb. 2, 1915.

Application filed November 8, 1909, Serial No. 526,680. Renewed November 18, 1914. Serial No. 872,845.

To all whom it may concern:

Be it known that I, THURE LARSSON, a citizen of the United States, residing at Worcester, in the county of Worcester and 5 State of Massachusetts, have invented a new and useful Automatic Stopping Mechanism for Elevators, of which the following is a specification.

The object of this invention is to provide 10 a new and improved automatic mechanism for gradually stopping an elevator at the ends of its travel either up or down.

The principal purpose of the invention is to provide an improved engaging mechanism 15 between the car and a system of levers connected to the stop device which shuts off and stops the power which causes the elevator to ascend or descend.

The invention has been particularly de- 20 signed for use in connection with hydraulic elevators of the plunger type but it will be obvious from the description hereinafter contained that the same may be applied to any type of elevator.

25 The invention consists of the parts and combinations of parts described in this specification and illustrated in the accompanying two sheets of drawings in which,

Figure 1 is a partial sectional view of a 30 plunger elevator with improved mechanism applied thereto. Fig. 2 is a detailed view of the lever system employed at the bottom of the well for automatically stopping the car at the end of its downward travel. Fig. 3 is an elevation showing a modified form that 35 may be used for said lever mechanism. Fig. 4 is a plan view illustrating the arrangement of sheaves for the controlling levers. Figs. 5, 6 and 7 are detailed elevations of 40 the lever system employed at the top of the elevator well for stopping the elevator car at the limits of its upward travel. Fig. 8 is a sectional elevation on an enlarged scale 45 of the valve mechanism showing the main valve, pilot valve and the automatic stopping valve.

The improvements will be best understood by a detailed description of the parts.

A cylinder A is sunk in the ground, which 50 cylinder is of a length a little more than the travel of the elevator. This cylinder A has a stuffing box on its top end fitting and slid-

ing in which is a plunger C which carries and supports the car or platform D which is fitted to run up and down on guides secured in the elevator well. Attached to the top of the car are counter-balancing cables E which are trained over sheaves F journaled at the top of the elevator well. Counter-weights G are attached to the end of 60 the cables E, which counter-weights are fitted to run up and down on ways secured to the side of the elevator well. A to-and-fro connection pipe H communicates with the cylinder A. When water 65 under pressure is let into the to-and-fro pipe H the plunger is forced upwardly and the car ascends. When the to-and-fro pipe is connected to the exhaust, the weight of the car and plunger forces the water out of the 70 cylinder and the car descends. When the flow in the to-and-fro pipe is prevented, the car and plunger are held stationary.

The valve arrangement consists of a main valve M, which controls the admission of 75 water under pressure to the cylinder to cause the car to ascend, which controls the flow of water from the cylinder to the exhaust to allow the car to descend and which stops the flow in the to-and-fro pipe to hold the car 80 stationary. The main valve is shown in its central position so that the flow to or from the elevator cylinder is stopped and the car held stationary. The main valve is operated by a motor piston M', as shown in Fig. 85 8. The admission of pressure on the right side of the motor piston causes the main valve to move to the left, as shown in Fig. 8, to allow the pressure to flow into the elevator cylinder and the connection of the exhaust with this side of the motor piston causes the main valve to move to the right to 90 allow the elevator cylinder to connect to the exhaust.

The admission of pressure or exhaust to 95 operate the motor piston M' is controlled and regulated by a pilot valve P. The pilot valve is controlled by a rope mechanism operated by a lever in the car.

An automatic stop valve S is interposed 100 between the main valve and the to-and-fro pipe H to stop the movement of the car automatically at the limits of its upward or downward travel. This automatic stop

valve S is controlled by a cam arrangement on the elevator car operating a system of levers and rods arranged in the elevator well.

5 The mechanism for operating the pilot valve from the car is arranged as follows:— A lever I is mounted on a shaft J which is journaled in bearings on the main valve casing. Connected to one end of lever I is a rope K which is trained over a pulley L and under a pulley L' and is then carried up the elevator well and trained over a sheave N and connected to a take-up weight O mounted so as to be capable of a vertical movement in ways at the top of the elevator well. Another rope K' is connected to the other end of the lever I and is trained over a pulley Q and under a pulley Q' and is then carried up the elevator well and trained over pulley R and connected to the take-up weight O. Pulleys L and Q' are mounted on a stud fixed in one end of an arm T, and pulleys L' and Q are mounted on a stud fixed in the other end of the arm T. The arm T is secured to a shaft U journaled in bearings on the bottom of the elevator car. A lever V is connected to the shaft U and is arranged to extend inside of the car or cage and to form the hand-operating or controlling lever by which the car attendant causes the car to go up or down or to be brought to a state of rest. This lever V operates with a suitable guide arranged inside of the car as shown. A movement of 35 the lever V to the left, as shown in Fig. 1, moves the right-hand end of the lever I upwardly and the left-hand end downwardly. A movement of the lever V to the right moves the left-hand end of the lever I upwardly and the right-hand end downwardly. The weight O is heavy enough to keep the ropes K and K' under tension and to allow for any expansion or contraction thereof. By this means the operator can operate the 45 pilot valve through the following connections:—Forming part of the lever I, or secured on the shaft J of the lever I is a small lever 10 which connects by a link 11 to a floating lever 12, the upper end of which is connected by a link 13 to the stem p of the pilot valve P and the lower end of which is connected to the stem m of the main valve M. These connections form restoring means which operate as hereinafter described to restore the pilot valve to central or closed position after the main valve has moved in the proper direction and distance called for by the movement of the lever V. The pilot valve casing is mounted on top of the main 55 valve casing. This pilot valve has three ports; the left-hand one a, as shown in Fig. 8, connects with the pressure chamber in the main valve; the right-hand one b connects with the exhaust by an outside pipe X; and the middle one c connects with the right-

hand side of the main valve casing through a passage-way Z. The pilot valve consists of two packings 14 and 15 arranged on the stem p of the pilot valve and held in proper relative position by suitable bushings slid thereon. A washer is arranged on the end of the stem p and the bushings are held in place by a nut threaded on the end of the stem p. The middle bushing is turned down so as to allow a reduced section or area between the two packings 14 and 15. The packings and bushings slide or operate in a brass tubing t which is driven into the pilot valve casing and which has ports cut therein to communicate with the passages a, b and c. The brass tubing t is provided with stuffing boxes at both ends so that the bushings will work tightly therein.

When the left-hand end of the lever I is moved downwardly as shown in Fig. 8, the lever 10 is moved to the left and link 11 pulls lever 12 to the left, which through link 13 moves the pilot valve to the left. This connects the passage Z through ports a and c to the pressure and the pressure acting on the motor piston M' moves the main valve to the left and allows water under pressure to flow to the elevator cylinder to cause the car to go up. As this movement of the main valve takes place, the main valve stem m will pull the lever 12 which, turning on link 11 as a fulcrum, will draw the link 13 and pull the pilot valve back to the right to its central or neutral position.

When the left-hand end of the lever I, as shown in Fig. 8, is moved upwardly back to the position from which it was moved downwardly to cause the car to ascend, the lever 10 will be rocked to the right and the pilot valve through link 11, lever 12 and link 13 will be moved to the right which will connect passage Z to the exhaust passage X through ports b and c. This will allow the main valve to move to the right until it comes back to its central or closed position, as shown in Fig. 8. As this action takes place the link 12 turning on link 11 as a fulcrum will restore the pilot valve to central position.

If it is desired to cause the car to go down, the lever 10 is rocked to the right from its central position, which will move the pilot valve to the right and again cause the main valve to move to the right to connect the to-and-fro pipe H to the exhaust. A movement of the lever 10 back to the position shown in Figs. 1 and 8 will cause the main valve to move back to its central position. The operation of these connections causes the main valve to move to the right or to the left in the same ratio that the pilot valve is moved to the right or to the left, and then restores the pilot valve to its central or neutral position so that the movement of the main valve corresponds exactly

with the movement of the lever 10 or with the movement of the lever V in the car.

The main valve consists of a sliding tube *d* screwed on the end of the main valve stem *m*. A bushing *e* is arranged on the tube *d* and is held in place thereon by a reduced tube *f* engaging the right-hand end of which is the motor piston *M'*, the parts being held in position by a nut *g* threaded 10 on the valve stem *m* and pressing the parts up against a shoulder *h* formed on the left-hand end of the main valve tube *d*. Connected to the main valve casing is a pressure pipe *i* and the exhaust pipe *j* and a to-and-fro passage *W* leads from the main valve casing and connects to the to-and-fro pipe *H* through the automatic shut-off valve *S* hereinafter described.

Arranged between the motor piston *M'* and the reduced bushing *f* is a packing 16. Arranged between the reduced bushing *f* and a shoulder on the bushing *e* is a packing 17. Arranged between the bushing *e* and the shculder *h* on the tube *d* is a packing 18. The packing 16 causes the motor piston to fit tightly to the main valve casing and the packings 17 and 18 cause the main valve to work tightly. The packing 16 works in a brass bushing 140 driven on 20 the right-hand end of the main valve casing and the packings 17 and 18 work in a brass bushing 150 driven in the left-hand end of a valve casing. Ports *k* are cut in this bushing 150. The tube *d* is bushed with 25 brass and runs on a piston 19 which is secured to a stem 20 which is threaded into a cap or head *n* secured to the left-hand end of the valve casing. Pressure is admitted through openings 21 into the reduced bushing *f* and through openings 22 in the main valve tube *d* into the space 23 at the right of the piston 19. The piston 19 is made smaller than the motor piston *M'*. By this arrangement, when pressure is let on the 30 right of the motor piston *M'* the main valve will be moved to the left, the water in the space 23 being forced through openings 22 and 21 back into the pressure. When the space at the right of the motor piston *M'* is 35 connected to the exhaust, the pressure on the left of the motor piston *M'* will move the same to the right, the space 23 filling up through passages 21 and 22. The motor piston *M'* and the piston 19 thus form in 40 effect a differential piston for giving the proper movements to the main valve. The packings 17 and 18 are arranged so that when the main valve is in its central position, the ports *k* will not be connected with 45 either pressure or exhaust, as packings 17 and 18 will inclose the ports and so that when the main valve moves to the left from the position shown in Fig 8, pressure will 50 flow through the main valve from pipe *i*, and so that when the main valve is moved 55

to the right from the position shown in Fig. 8, the exhaust pipe *j* will be connected to the passage *W*.

The details of the valve are not claimed in this application for patent owing to the classification adopted in the Patent Office, but the same are claimed in a companion application filed by me Nov. 8, 1909, Serial No. 526,679.

The automatic stop valve *S* consists of a 75 casing 24 secured on the top of the main valve casing. A brass tube *l* is driven in the same. Ports 25 are cut therein opposite the pipe *W* and ports 26 opposite the to-and-fro pipe *H*. The stop valve consists of 80 a tube *s* which has shoulders fitting against which are valve heads *q* and *r* held in place by collars *u* and *u'*. A packing 27 is arranged between the valve head *q* and the collar *u* and a packing 28 is arranged between the valve head *r* and the collar *u'*. 85

Stems 29—29 are secured to the ends of the tube *s* by collars 290, which collars are threaded on the ends of the tubes *s* and which have shoulders to hold the collars *u* and *u'* in position. These stems project 90 out through stuffing boxes *v* secured to heads attached to the ends of the stop valve casing 24 and balance the valve hydraulically.

The operating mechanism hereinafter described may be connected to either stem 29—29 as the exigencies of the location demand. In the drawings the mechanism is shown as connected to the left-hand stem 29. 95

Holes 30 are arranged in the collars 290 so that the stop valve can move freely back and forth in the casing. Spring-pressed check valves 31—31 are arranged to cover 100 openings in the tube *s*, the check valves being arranged to close toward the tube. When the elevator is going up, pressure is flowing from the pressure pipe *i* through the main valve through the pipe *W* to the pipe *H*. When the elevator reaches the 110 limits of its upward movement by the automatic mechanism hereafter described, the stop valve is moved to the left bringing the packing 28 to prevent flow through the ports 26 and thus stopping the flow 115 of water between pipes *W* and *H* and stopping the upward movement of the elevator. When the operator in the car reverses the position of the main valve for the downward movement, pipe *W* is connected through the main valve to the exhaust pipe *j*. Then the flow from the elevator cylinder will start through pipe *H*, through the right-hand openings 30; through 120 the center of the tube *s* and out through the check valves 31—31 which will open to allow this flow to start. As the elevator starts on its downward movement the stop valve will be moved to its central or inoperative position shown in Fig. 8, by the auto- 125 130

matic mechanism hereafter described, and when the car is fully on its downward movement, water will flow from pipe H through ports 26, ports 25 to the pipe W and out to the exhaust pipe j through the main valve. As the car approaches the bottom of its downward run the stop valve will be moved to the right by the automatic mechanism hereafter described. This will cause the packing 27 to move to the right of the ports 25 and will check and stop this flow. When the attendant on the car reverses the position of the main valve to allow pressure again to flow into pipe W for an upward movement of the car, water will then flow through the left-hand openings 30, the center of the tube s and out through the check valves 31—31 into pipe H. This will allow the car to start on its upward travel and as this travel takes place, the automatic mechanism hereinafter described will restore the shut-off valve to its normal central inoperative position shown in Fig. 8. Thus the automatic valve will check and stop the elevator at the limits of its run either up or down but will allow the elevator to start in the opposite direction after it has been stopped by the automatic valve. It also will be seen that this automatic stop valve can be easily manufactured as the same has to be bored for but one diameter.

The automatic mechanism for operating and controlling the stop valve is arranged as follows:—A lever 32 is mounted on a shaft journaled in bearings secured to the top of the valve casing 24. Secured on the ends of this shaft is a lever 33 which connects by a link 34 to one of the valve stems 29 of the shut-off valve. Connected to the ends of the lever 32 are rods 35 and 36 which are made in sections secured together by suitable couplings and which rods extend up at the side of the elevator well. The rods 35 and 36 are connected preferably at the couplings to T-shaped levers 37, 38 and 39 arranged at the bottom of the elevator well and turning on studs or shafts secured to supports or brackets y which are fastened to the side of one of the guides z for the elevator car. The downwardly extending arms of the T-shaped levers 37, 38 and 39 have bearing members shown as rollers or shoes 40 arranged on their ends. These downwardly extending arms of the T-shaped levers stand at slightly different angles so that the shoe 40 on the upper lever 39 is farthest to the right, as shown in Fig. 2.

Arranged on the elevator car are two guide pieces 41 and 42, the space between which forms a cam-way inclined from the top of the car to the bottom of the car toward the left. The ends of the guide pieces 41 and 42 are curved outwardly so that the inclined cam-way will have wide mouths to engage easily with the rollers or shoes 40.

At the top of the elevator well are arranged three similar T-shaped levers 43, 44 and 45 which have similar rollers or shoes 40. These uppermost levers are shown in their normal position in Fig. 6. As the car approaches the upward limit of its run, the inclined cam-way first engages the shoe on the lever 45 and swings the same to the left. Before the cam-way leaves this shoe it engages the shoe on lever 44 and continues the left-hand movement of the shoes or rollers 40, and as the car goes still farther up, the cam-way engages the shoe on lever 43 and continues the left-hand movement of the rollers or shoes 40 until the car reaches the limits of its upward run to which the mechanism is set, which is indicated in Fig. 7. The principle of this motion is that after the first engagement of the cam-way with the shoe or roller on the lever 45, the cam takes up and engages the next shoe on the lever 44 before it leaves the shoe on lever 45 and before the cam-way leaves the shoe on lever 44 it engages the shoe on lever 43. By this engagement an easy continued rocking motion is given to the levers as the car approaches the limits of its upward run and the parts can be adjusted so that the stopping motion can take place in any desired movement of the elevator car, say a thirty-foot movement.

As the car moves downwardly from its upward limit of travel, shown in Fig. 7, to a position where the cam-way progressively disengages the rollers or shoes on the levers 43, 44 and 45, the levers will be restored to normal position, as shown in Fig. 6.

As the car reaches the bottom of its downward run, the lower mouth of the cam-way will first engage the roller or shoe on lever 39 and will move the same to the right and then before leaving the shoe on lever 39 will engage the shoe on lever 38 and will continue the right-hand movement, and then before leaving the shoe on lever 38 will engage the shoe on lever 37 and will still continue the right-hand movement of the shoes or rollers which will bring the lever 32 to the position shown in Fig. 1.

The elevator car is shown at its lowest extreme in Fig. 1. As the car starts upwardly from its lowest position, the cam-way will disengage progressively from the shoes on levers 37, 38 and 39 and will restore the operating system of levers to normal position shown in Fig. 6. Thus a very simple mechanism is provided for operating the automatic stop valve. Instead of using a single T-shaped lever, bell-crank levers 46 and 47 may be connected to the system of rods 35 and 36. These bell-crank levers may be pivoted on a suitable support 48. The downwardly extending ends of these levers may be connected to a block 49 on which

may be arranged a shoe 50 shaped so that the inclined cam-way on the elevator car can easily engage the same. This arrangement of levers is used when it is desired to give the shoes or rollers large bearing surfaces and give an easy acting device, as the two levers will give a parallel motion to the shoe. As many levers can be arranged at the top and bottom of the elevator well as desired so that any desired motion can be given to the lever 32. Thus a very efficient mechanism is provided for operating the automatic shut-off valve.

The general design of the mechanism herein described has been to make all the parts simple, efficient, easy of repair and so that they can be manufactured in large lots and used interchangeably in different relative positions to meet the different locations encountered in adapting the mechanism to different plants.

The details and arrangements herein shown and described may be greatly varied by a skilled mechanic without departing 25 from the scope of my invention as expressed in the claims.

Having thus fully described my invention what I claim and desire to secure by Letters-Patent is:—

30 1. The combination with the end run stopping device for an elevator, of a cam mounted on the car, and a series of shoes, each connected to the stopping device which the cam progressively engages and disengages as it approaches the end of the run, whereby the end run stopping device will be progressively operated.

2. An automatic mechanism for operating and controlling the end run stopping device 40 of an elevator, comprising a cam on the car, and two series of shoes, one arranged at the top and the other at the bottom of the run, said shoes being connected to the stopping device and said cam being arranged to engage and disengage said shoes progressively.

3. An automatic mechanism for operating and controlling the end run stopping device of an elevator, comprising an inclined cam-way arranged on the car and a plurality of bearing members connected to the stopping device, said cam-way being arranged to engage and disengage said bearing members progressively.

4. An automatic mechanism for operating and controlling the end run stopping device 55 of an elevator, comprising an inclined cam-way arranged on the car, a series of bearing members arranged at the top of the elevator well, and a series of bearing members arranged at the bottom of the elevator well, said bearing members being connected to the stopping device and said cam-way being arranged to engage and disengage said bearing members progressively.

65 5. An automatic mechanism for operating

and controlling the end run stopping device of an elevator, comprising an inclined cam-way on the car, a pair of rods extending up the elevator well, and a series of levers connected to said rods and carrying bearing 70 members, said cam-way being arranged to engage and disengage said bearing members progressively.

6. An automatic mechanism for operating and controlling the end run stopping device 75 of an elevator, comprising an inclined cam-way on the car, a pair of rods extending up the elevator well, a series of levers connected to said rods at the top of the well, and a series of levers connected to said rods at the bottom of the well, said levers carrying bearing members and said cam-way being arranged to engage and disengage said shoes progressively.

7. An automatic mechanism for operating 85 and controlling the end run stopping device of an elevator, comprising an inclined cam-way arranged on the car, brackets or supports arranged at the side of the elevator well, a series of levers carried by said supports, a pair of rods connected to the stopping device and to said levers, and bearing members carried by said levers, said cam-way being arranged to engage and disengage said bearing members progressively. 95

8. An automatic mechanism for operating and controlling the end run stopping device of an elevator, comprising an inclined cam-way having wide or open mouths, and a series of bearing members arranged at the 100 top and the bottom of the elevator well which said cam-way progressively engages and disengages.

9. An automatic mechanism for operating and controlling the end run stopping device 105 of an elevator, comprising an inclined cam-way mounted on the car, a pair of rods connected to the stopping device and extending vertically in the elevator well, a series of levers connected to said rods at the top of 110 the well, another series of levers connected to said rods at the bottom of the well, and bearing members carried by said levers which the said inclined cam-way is adapted to engage and disengage progressively. 115

10. An automatic mechanism for operating and controlling the end run stopping device of an elevator, comprising an inclined cam-way arranged on the car, a pair of rods connected to the stopping device and extending vertically in the elevator well, and pairs of bell-crank levers connected to said rods arranged in series, the free ends of each pair of said levers carrying a shoe and the said inclined cam-way being arranged to 120 engage and disengage said shoes progressively. 125

11. An automatic mechanism for operating and controlling the end run stopping device of an elevator, comprising an inclined 130

6
cam-way, a pair of rods connected to the stopping device, and a series of levers standing at different angles and carrying bearing members which said inclined cam-way engages and disengages progressively.

12. An automatic mechanism for operating and controlling the end run stopping device of an elevator, comprising an inclined cam-way carried by the car, a series of supports connected to one of the guides for the elevator car, series of levers mounted on said supports, a pair of rods connected to the stopping device and operated by said levers, and bearing members carried by said levers 15 with which the cam-way progressively engages and disengages.

13. The combination with the end run stopping device for an elevator, of a plurality of movable mechanical members arranged along the path of the car, and all connected with said stopping device for operating the same, and a single means carried by the car for engaging the first one of said members and moving it to start the 25 stopping device, and for thereafter success-

sively engaging each subsequent one of said members and moving it to cause the stopping device to operate with gradually increasing effectiveness.

14. The combination with an end run 20 stopping device for an elevator, of a series of means arranged at the top of the elevator well in the path of the car, a series of means arranged at the bottom of the elevator well in the path of the car, all said means being 25 connected to said stopping device, and means carried by the car for engaging the first one of each of said series and moving it to start the stopping device into operation and for engaging each subsequent one and 30 moving it to operate the stopping device to a greater degree as the car reaches the limit of its run in either direction.

In testimony whereof I have hereunto set my hand, in the presence of two subscribing witnesses.

THURE LARSSON.
